SHEET TRANSFERRING DEVICE

George W. von Hofe, Bound Brook, N. J., assignor
to New Jersey Machine Corporation, Hoboken,
N. J., a corporation of New Jersey

Application November 4, 1937, Serial No. 172,721

3 Claims. (Cl. 294—64)

The invention relates to devices for transferring sheets of material, exemplified for instance by labels and the like, and more particularly to devices whereby sheets of materials are individually removed from a stack or other source of supply and transferred or conveyed to another point at a distance from said stack or other source of supply.

In many existing types of labeling and other machines it is the practice to pick up labels or other sheets in individual succession from a stack or other supply by means of a suction head which is subsequently operated to transfer said labels or other sheets to another point in the machine as exemplified for instance by the labeling station of labeling machines. In many cases, each label, as it is carried and conveyed by the suction head, is passed in operative relation to an adhesive applying means, and receives therefrom a coating of adhesive prior to the arrival of the suction head at the labeling station. Very often the labels or equivalent sheets are more or less deeply embossed or are otherwise of uneven surface contour. This unevenness of the surfaces of said labels or equivalent sheets interferes with the efficiency of the suction action of the suction head and prevents the latter from developing an effective suction hold upon said labels or other sheets with the result that the operation of said suction head in the intended manner is faulty and unreliable. Because of the leaky suction connection resulting from said unevenness of surface, the suction head oftentimes is completely incapable of removing individual labels or other sheets from the stack or other supply.

The object of the invention is to provide a novel transferring device of the indicated type in which the aforesaid objections and others inherent in existing arrangements are entirely overcome and which automatically conforms itself to the surface of the label or other sheet regardless of its contour to thereby develop a co-operating surface engagement whereby a suction grip or hold of maximum efficiency by said device is definitely assured. Other more specific objects of the invention will appear from the description hereinafter and the features of novelty will be pointed out in the claims.

In the accompanying drawing, which illustrates an example of the invention without defining its limits, Fig. 1 is a sectional elevation of a sheet transferring device embodying the novel features with the parts in normal position; Fig. 2 is a similar view showing the transferring device with a label or other sheet of material carried thereby;

Fig. 3 is a face view of the novel transferring device, and Fig. 4 is an enlarged fragmentary section similar to Fig. 2.

In all of its forms, the novel transferring device includes what may conveniently be referred to as a carrier or suction head arranged for connection with a suitable source of suction and provided with flexible sealing means in operative relation to that part of the carrier at which the suction is effective to develop a pick-up and holding force. In every instance, the arrangement is such that the inherent flexibility of the sealing means is relied upon to enable the latter to automatically conform itself to the surface of the label or other sheet regardless of the contour thereof. That is to say, the flexible sealing means, when brought into contact with a label or other sheet, for instance, in the operation of removing the same from a supply, automatically develops an airtight suction connection with the surface of said label or other sheet to thereby insure a suction hold of maximum efficiency thereon. This result is attained whether the surface of the label or other sheet is smooth and even, or whether said surface is embossed or otherwise of uneven contour.

For purposes of description, and for no other reason, the novel transferring device is illustrated in a form particularly adapted for use in existing types of labeling machines. It is accordingly to be understood, even though the following specification refers specifically to labels and labeling machines, that this is done merely to simplify the description and without any intent to thereby indicate the range of usefulness of the novel device.

As shown in the drawing, the carrier or suction head of the transferring device includes a hollow member 5 having an interior suction chamber 6 which is suitably connected, as by means of a nipple 7 and flexible tube 8, with any convenient source of suction. In practice, suitable provision is made to control the suction connection so that suction will be automatically produced in the chamber 6 and cut off in proper synchronism with the transferring operations of the device; as such control specifically does not constitute a feature of the novel device, it has not been deemed necessary to illustrate any means for effecting the same. The member 5, in the machine of which it forms a part, is reciprocated in horizontal directions so as to travel between a pick-up station at which the successive terminal labels are removed from a stack or other supply, and a labeling station at which the labels carried by

the device are deposited upon the articles for which they are intended. For this purpose the member 5 may, as shown, be provided with an upright rod 9 whereby said member 5 is suspended from any customary type of reciprocable carriage arranged to be operated in the intended manner by any conventional form of mechanism; as neither the reciprocable carriage nor the mechanism, nor any of the elements associated therewith, specifically constitute a part of the instant invention, no example thereof is included in the drawing.

The carrier or suction head of the device in its illustrated form further includes a block 10 which may constitute an integral part of the member 5 or be suitably secured thereto in any convenient manner, and in any case is mounted on the member 5, for instance, in the manner shown in Figs. 1 and 2. The dimensions and shape of the block 10 may be varied in accordance with the requirements of the specific arrangement of which it forms a part; in the drawing, the block 10 is relatively smaller in size than the member 5 and is of rectangular form as shown in Fig. 3. The block 10 of the carrier has its active surface provided with a suction area at which the developed suction is effective and in the specific example shown in the drawing includes at least one opening extending transversely therethrough at said suction area for the accommodation of a flexible mouthpiece which automatically conforms itself to varying surface contours to develop an air-tight suction connection with a given surface. The aforesaid transverse opening may, as shown, consist of an internally threaded section 11 and an outwardly flaring or diverging section 12 forming a downward continuation thereof, as shown in Figs. 1, 2 and 4. The threaded section 11 of the aforesaid mouthpiece opening is preferably located in concentric registry with a suction port 13 which communicates with the chamber 6 of the member 5, as shown in Figs. 1 and 2.

The diverging or outwardly flaring section 12 of the block opening constitutes a seat for the flexible sealing means illustrated in the form of a mouthpiece or suction cup 14 of rubber or other flexible material, which is so dimensioned and positioned that in its normal condition said cup 14 projects downwardly beyond the block 10 with its peripheral edge which preferably is highly resilient, located below the lower surface of said block 10, for instance as indicated in Fig. 1. The mouthpiece or suction cup 14 is fastened in place in any suitable manner, preferably so as to be easily removable at will, as for instance by means of a fastening member exemplified in the form of a screw 15 which screws into the section 11 of the block opening and is provided with a bevelled head 16 whereby the cup 14 is clamped in place in the outwardly diverging section 12 of the block opening. The head 16 of the screw 15 is preferably dimensioned so as to fill the major portion of the interior of the suction cup 14 and to leave only the restricted peripheral edge portion thereof, which is preferably very resilient or flexible, free to conform itself to the contour of the surface to which it is applied in the operation of the device. To establish communication between the suction chamber 6 and the suction cup 14, that is the space enclosed by the peripheral edge thereof below the head 16, the screw 15 may be provided with an axial passage 17 arranged to register with the suction port 13 of the member 5

in the operative assembled condition of the parts as illustrated in Figs. 1 and 2.

In the operation of machines of which the type of transferring devices selected for illustrative and descriptive purposes forms a part, these devices, as previously stated herein, are reciprocated horizontally for instance, between a label pick-up station and a label applying station. During the operative movements of such transferring devices, the labels carried thereby are brought into contact with adhesive applying means and receive a surface coating of adhesive therefrom prior to the arrival of the device at the label applying station; during the inoperative return movements of said devices, the latter do not contact with said adhesive applying means, this being a customary and well-known arrangement.

In the drawing, the adhesive applying means is exemplified by an adhesive applying roll 18 which receives a surface supply of adhesive in any conventional manner and generally is provided with circumferential grooves for the accommodation of pick-off or stripping members 19 which prevent the label from being stripped from the transferring device and carried around on the roll 18. With this type of adhesive applying means, the labels carried by the transferring device are passed in progressive tangential contact with the roll 18 and thus receive a surface coating of adhesive therefrom. To insure an efficient application of the adhesive to the labels by the roll 18 or its equivalent, it is desirable and even necessary to provide a preferably rigid backing or support for the labels during the travel in progressive tangential relation to said roll 18.

This backing or support may be provided in any suitable manner and in some arrangements may be afforded by the block 10, for instance, if the labels are not large enough to project beyond the same. In the case of labels of larger dimensions, as shown in the illustrated example, the block 10 may carry a rigid backing or supporting plate 20 which preferably is made of comparatively thin material and removably fixed in place in any convenient manner, as by screws 21, and is provided with an opening 22 in registry with and for the accommodation of the peripheral edge portion of the suction cup 14; if more than one suction cup 14 are included in the device, a corresponding number of additional openings 22 will be formed in the plate 20 at the proper places. It is to be understood that the opening 22 of the plate 20 need not be centralized thereon as shown, but may be otherwise located for the accommodation of the peripheral edge portion of the suction cup 14; in other words, the plate 20 need not be symmetrically mounted on the block 10. Because the plate 20 is carried across and in tangential relation to the adhesive applying roll 18 in the operation of the device, it is in any case preferred to shape and dimension the plate 20 in accordance with the shape and size of the labels for which it is designed; in passing over the roll 18, the surface of the plate 20 is thus substantially covered and protected by the label which is carried by the device at the time and therefore does not become covered or soiled with adhesive picked up from the roll 18.

Normally, the parts of the illustrated device are in the position shown in Fig. 1 in which the suction cup 14 projects through the opening 22 of the backing plate 20 and beyond the lower surface thereof. In the operation of the ma-

chine of which the transferring device forms a part, the member 5 and block 10 with their associated parts, are moved into contact with the terminal end of a stack of labels or equivalent sheets, or with a corresponding source of supply. As the block 10 or the plate 20, if it forms a part of the arrangement, approaches the stack or other source of supply, the free edge of the suction cup 14 will finally be brought into surface engagement with the surface of the terminal label or equivalent sheet *a*. As shown in Fig. 4, the inherent flexibility of the free peripheral edge of the suction cup 14 causes the aforesaid free edge thereof to conform itself automatically and accurately to the surface contour of the label or other sheet *a* even though the latter may be deeply embossed as is diagrammatically indicated in Fig. 4. If the surface contour of the label or equivalent sheet is smooth and even, the free edge of the suction cup 14 will likewise accommodate itself to such surface. In any event, regardless of the surface contour of the label or other sheet *a*, the suction cup 14 will develop an air-tight suction connection with the surface of the label and thereby insure maximum efficiency in the suction hold whereby the label or other sheet *a* is held in place on the device.

After the label or other sheet *a* has been picked up in the manner described, it will be carried along for instance in a horizontal path, and during this travel may engage an adhesive distributing means, or more specifically may be passed in progressive tangential contact with the adhesive distributing roll 18, as illustrated in Fig. 2. During these operative steps the plate 20 or its equivalent, will function as a backing to properly support the label or other sheet *a* in a manner to provide for the proper and uniform distribution of an adhesive coating thereon by the roll 18 or other adhesive distributing means. As previously stated herein, the plate 20 is preferably of a form and dimensions to conform to the form and dimensions of the labels or other sheets *a* for which it is designed, so that when a label or other sheet *a* is held in place by the suction cup 14, the surface of the plate 20 will be covered by said label or other sheet *a*, and will thereby be protected against contamination by adhesive during the adhesive coating step mentioned above. Because of the fact that the head 16 of the screw 15 substantially fills the interior of the suction cup 14, the surface of said head 16, in the illustrated arrangement lies substantially flush with the outer surface of the plate 20; suction is therefore exerted on the label or its equivalent only through the passage 17, while the suction connection with the label or its equivalent is made air-tight by the flexible peripheral edge of the suction cup 14 which conforms itself to the surface contour of said label or its equivalent. This arrangement prevents the label or its equivalent from being cupped out of its plane and consequently avoids dry spots free from adhesive on the labels as the latter pass over the adhesive distributing roll 18 or its equivalent.

If the label or other sheet *a* which is being held in place by the suction cup 14 sags slightly at the forward advancing end of the plate 20, the stripping members 19 in addition to their other functions, will guide the sagging portion of said label or other sheet *a* toward the periphery of the adhesive distributing roll 18; these stripping members 19 further serve to prevent

the label or other sheet *a* from being carried by the roll 18 on its surface or, in other words, strip said labels or other sheets *a* from said roll 18 in the conventional and well-known manner.

The device is of maximum efficiency in operation and makes it possible to adequately and easily handle labels or other sheets having embossed surfaces or uneven surface contours of other types, and enables such labels to be easily and individually picked from a supply and transferred to a point at a distance from said supply. If, because of the dimensions or other inherent characteristics of any particular type of labels or other sheets, it should become necessary or desirable to do so, the suction cups 14 may be duplicated in such numbers as may be required and so located as to provide efficient suction holds upon the particular labels or other sheets at various points of the surfaces thereof. It will be noted in the operation of the device that the suction is effective on the label or its equivalent only through the passage 17 and within the interior of the free peripheral edge of the suction cup 14 and thereby provides a localized and strong suction grip; this fact in addition localizes the contact area of the suction cup with the label or other sheet and positively insures the air-tight suction connection between the suction cup 14 and the surface of a given label or other sheet. It will, of course, be understood that the suction is made effective at the suction cup 14 and discontinued thereat in proper mechanical synchronism with the particular operations being performed by the device at the time.

The device may be adapted for efficiently handling labels of varying shapes and dimensions by simply removing one plate 20 and substituting another of the required type, instead of removing the entire block 10 or its equivalent as has heretofore been necessary in many existing types of labeling machines; the change over from one class of labels to another is thus reduced to the simplest operation and at the same time the equipment necessary to effect the changes is inexpensive and economic both in the matter of time consumed in making the change and in the cost of parts.

A particularly desirable feature incidental to the novel device which contributes materially to its efficiency resides in the fact that the free peripheral edge of the suction cup 14 is very resilient and is deflected into the opening 22 of the plate 20 by air pressure on the label or its equivalent as suction is applied to the face thereof.

Various changes in the specific forms shown and described may be made within the scope of the claims without departing from the spirit of the invention.

I claim:

1. A sheet transferring device comprising a suction head arranged for connection with a source of suction, a rigid backing plate carried by said suction head and provided with an opening, and a flexible mouthpiece carried by said suction head and normally projecting outwardly through said opening beyond said backing plate, said mouthpiece conforming itself to varying sheet surface contours and flexing into said opening to develop a localized air-tight suction connection with a predetermined portion of said sheet, the latter outside of said localized connection lying in surface engagement with said backing plate.

2. A sheet transferring device comprising a suction head arranged for connection with a

source of suction, a rigid backing plate carried by said suction head and provided with an opening, said backing plate being dimensioned and shaped to correspond substantially with the dimensions and shape of a predetermined label or the like, and a flexible mouthpiece carried by said suction head and normally projecting outwardly through said opening beyond said backing plate, said mouthpiece conforming itself to varying label surface contours and flexing into said opening to develop a localized air-tight suction connection with a predetermined portion of said label, the latter outside of said localized connection lying in

conterminous surface engagement with said backing plate.

3. The combination of a suction mouthpiece having a suction port through which a localized suction hold is developed on a predetermined portion of a label or its equivalent, and a rigid backing plate removably carried by said mouthpiece in predetermined relation to said suction port, and being shaped and dimensioned to correspond with the shape and dimensions of said label or its equivalent, the latter outside of said localized suction hold lying in conterminous surface engagement with said backing plate. 5

GEORGE W. VON HOFE.
